UNITED STATES PATENT OFFICE.

HENRY E. REEVE, OF BROOKLYN, NEW YORK.

GONG CONSTRUCTION.

1,285,381.

Specification of Letters Patent. Patented Nov. 19, 1918.

Application filed June 12, 1916. Serial No. 103,085.

To all whom it may concern:

Be it known that I, HENRY E. REEVE, a citizen of the United States of America, residing at Brooklyn, New York, have invented a new and useful Gong Construction, of which the following is a specification.

My invention relates particularly to the mounting of the gong top or bell and the abutment for the striker or hammer. It is intended especially for what are known as electric bells or gongs, the striker of which is operated by electric current.

The main object is to provide a strong, simple and inexpensive construction for supporting a gong top so that it will be held from rotation.

Another object is to provide a durable buffer or cushion for the hammer which will take up the shock of the rebound but without itself causing the hammer to rebound and at the same time reduce the sound of the shock to a practicable minimum.

Figure 1 is a front view of a construction embodying the improvements of my invention, part of the gong top being broken away to illustrate the important details of construction.

Fig. 2 is a fragmentary section on the plane of the line $x-x$ of Fig. 1.

Fig. 3 is an end view of the post or support for the gong top.

Fig. 4 is a view of a fragment of the gong top showing the shape of the opening at the center.

Fig. 5 is a detail view of a washer.

The operating mechanism of any suitable type may be mounted, for instance, in the casing 10. The hammer 11 is pivoted at 12 and suitably connected by means not shown with the operating mechanism.

The gong top or bell 13 is supported by bracket 14 which has a forwardly projecting post 15. The gong top is secured to the post by means of a bolt or screw 16 whose shank passes through the hole 17 in the gong top and screws into a threaded socket 18 in the post. The post is also provided with one or more, preferably two, pins 19 fixed rigidly in the outer end and adapted to project into

pockets such as 20 at the side or sides of the hole 17. The pins 19 are preferably arranged somewhat to one side of a diameter of the socket 18 and the pockets 20 are correspondingly located with reference to the center of the hole 17 so that the gong top can be assembled on the post and the pins 19

in one position only. This prevents anyone from putting the gong top on wrong side up and insures accuracy and permanency of adjustment. Preferably the walls 21 of the pockets 20 are substantially radial so as to provide a maximum resistance to rotation of the gong top without developing any cam action. I also preferably provide a washer 22 having a central opening 23 for the shank of the screw 16 and having lateral openings 24 for the outer ends of the pins 19. This ties together the ends of the pins and also affords a seat for the underside of the head of the screw.

By making the hole 17 for the shank of the screw and the pockets 20 open into each other, it is possible to form the opening and pockets with a single punch which is inexpensive and durable. It has been found that gong tops of hot pressed tool steel are not only cheaper than brass, but afford a louder tone. This steel in most cases is so hard that even high speed drills will not last long and in many cases are of no use in drilling holes of a small size. It has been found practically impossible to punch such small holes in tool steel. I have found that by the construction herein shown and described it is possible to punch the hole for the stud or fastening screw and the pockets for the pins simultaneously at small expense and at the same time provide a construction which will hold a gong top satisfactorily.

In the construction shown, the hammer is mounted beneath the gong top and normally hangs as shown in position to be propelled upwardly and outwardly to strike the inner edge of the gong top. In such a construction it is necessary to provide a stop or abutment for the hammer but the ordinary solid stop jars the mechanism and also makes considerable noise and sometimes causes a number of small vibrations which cause it to rattle and interfere with the clear tone which the gong should produce. To avoid this I have provided a simple, inexpensive but reliable cushion stop. This consists of a projection 26 at one side of the post 15 and a metallic face plate 27 riveted to it but with a layer of cushioning material 28 interposed. The parts may be riveted together as indicated at 29. With the proper cushioning material properly held between the rigid projection 26 and the face plate 27 a stop is produced which brings the hammer to rest with very little shock or sound. Pref-

erably the cushioning material is non-vibrating, such as rubber cloth with a layer of canvas, or such as leather or a material having similar characteristics, and the face plate 5 is preferably somewhat soft or at least non-resilient.

What I claim is:—

1. In a construction of the character described, the combination with a supporting 10 post and a stud carried thereby, of a hard metal gong top having a centrally punched opening for said stud and a lateral pocket extending off to one side from said central opening and formed simultaneously with the 15 punching of said central opening and an upstanding member on the supporting post at the side of the stud on the supporting post and engaging in said lateral pocket to thereby position the gong top engaged on the 20 stud.

2. In a construction of the character described, the combination with a supporting post and a stud carried thereby, of a hard metal gong top having a centrally punched 25 opening therein for the stud and laterally extending pockets at opposite sides of said central opening, upstanding pins on the supporting post at opposite sides of the stud engaging in said laterally disposed pockets

and projecting beyond the face of the gong 30 top and a washer engaged over the gong top and having a central opening for the stud and laterally disposed openings at opposite sides thereof receiving the upstanding pins to thereby tie together the outer ends of 35 said pins.

3. In a construction of the character described, the combination of a supporting post having a lateral projection, a non-resilient metallic face plate, cushioning material 40 rigidly clamped between said face plate and said projection, a gong top carried by said post and a hammer adapted to strike against said gong top and against said face plate.

4. The combination with a supporting 45 post, a securing bolt on said supporting post and an upstanding projection on the supporting post on one side of said bolt, of a gong top of hard steel having punched therein a substantially centrally disposed bolt 50 receiving opening with a co-extensive laterally offset pocket, said gong top being secured on the post with the bolt engaged in the substantially centrally disposed opening and the upstanding projection engaged in the pocket offset to the side of the central opening.

HENRY E. REEVE.
